(57) **CLAIM**

The ornamental design for a case for a process control instrument, as shown and described.

DESCRIPTION

FIG. 1 is a perspective view of a case for a process control instrument.

FIG. 2 is a front elevation view thereof.

FIG. 3 is a rear elevation view thereof.

FIG. 4 is a top plan view thereof.

FIG. 5 is a bottom plan view thereof.

FIG. 6 is a left side elevation view thereof.

FIG. 7 is a right side elevation view thereof.

FIG. 8 is a cross-sectional view taken along line 8-8 in FIG. 2; and,

FIG. 9 is a cross-sectional view taken along line 9-9 in FIG. 2.

1 Claim, 9 Drawing Sheets

FIG. 1

FIG. 2

FIG. 3

FIG. 4

FIG. 5

FIG. 6

FIG. 7

FIG. 8

FIG. 9
